UNITED STATES PATENT OFFICE.

ALWINA D. POSTERT, OF PLEASANTON, TEXAS.

DESIGN FOR A BOUQUET-HOLDER.

SPECIFICATION forming part of Design No. 26,504, dated January 12, 1897.

Application filed November 10, 1896. Serial No. 611,681. Term of patent 7 years.

To all whom it may concern:

Be it known that I, ALWINA D. POSTERT, a citizen of the United States, residing at Pleasanton, in the county of Atascosa and State of Texas, have invented and produced a certain new and original Design for a Bouquet-Holder; and I do declare the following to be a full, clear, and exact description of the invention, such as will enable others skilled in the art to which it appertains to make and use the same.

My invention relates to a new and original design for a bouquet-holder for personal wear.

It relates to the entire configuration of the bouquet-holder, and especially to a bouquet-holder made of ductile wire.

My invention relates particularly to a bouquet-holder as illustrated in the accompanying drawing, in which the figure in the drawing is a perspective view of a bouquet-holder embodying my design.

The leading features of my design appear in the following description:

1 represents an ordinary safety-pin, from which a pair of circular parallel arms or 25 clasps 2, arranged at a right angle to the length of the body of said pin, project and in the same longitudinal plane.

The contiguous ends 3 3 of each clasp lie in the same plane as the body or shank of the 30 pin proper, and the immediate ends are bent back upon themselves in the same plane as the arm of which they are formed.

Having thus fully described my design, what I claim as new and useful, and desire to 35 secure by Letters Patent of the United States, is—

The design for a bouquet-holder, substantially as herein shown and described.

In testimony whereof I hereunto affix my 40 signature in presence of two witnesses.

ALWINA D. POSTERT.
